LAMP

Albert Austin Taber, Sr., Los Angeles, Calif.

Application December 27, 1948, Serial No. 150,394

Term of patent 3½ years

(Cl. D48—20)

To all whom it may concern:

Be it known that I, Albert A. Taber, Sr., a citizen of the United States, residing in Los Angeles, in the county of Los Angeles and State of California, have invented a new, original, and ornamental Design for a Lamp, of which the following is a specification, reference being had to the accompanying drawing, forming part thereof.

The single drawing figure is a perspective view of a lamp, showing my new design.

The dominant characteristics of my design reside in the portions shown in the drawing by means of full lines.

I claim:

The ornamental design for a lamp, substantially as shown and described.

ALBERT AUSTIN TABER, SR.
